UNITED STATES PATENT OFFICE.

HENRY B. COOLEY, OF NEW BRITAIN, CONNECTICUT, ASSIGNOR TO THE AMERICAN PAPER GOODS COMPANY, OF KENSINGTON, CONNECTICUT, A CORPORATION OF NEW JERSEY

DELIVERY MECHANISM FOR PRINTING-PRESSES.

1,008,014.

Specification of Letters Patent.

Patented Nov. 7, 1911.

Application filed January 25, 1910, Serial No. 539,941. Renewed March 23, 1911. Serial No. 616,486.

To all whom it may concern:

Be it known that I, HENRY B. COOLEY, a citizen of the United States, and resident of New Britain, in the county of Hartford and State of Connecticut, have invented a new and useful Delivery Mechanism for Printing-PresSES, of which the following is a specification.

My invention relates to delivery mechanism for printing presses with the object in view of providing means for separating printed sheets into different piles, either to afford the freshly deposited ink additional time to dry before being disturbed by a successive sheet deposited thereon or to separate differently printed sheets into piles of like printed matter when a press is run with independent groups of type printing successively on blanks fed thereto.

29 A practical embodiment of my invention is represented in the accompanying drawings in which,

Figure 1 is a view of a printing press in front elevation, Fig. 2 is a view of the same in end elevation, Fig. 3 is a vertical section from front to rear, and Fig. 4 is a partial front elevation.

The particular form of machine which I have chosen to illustrate my invention is of the type shown, described and claimed in my pending application Serial No. 539,942 filed of even date herewith, in which the form cylinder is provided with a plurality of flat beds for receiving chases of type and the impression cylinder, driven at variable rates of speed by the form cylinder, is provided with a plurality of impression segments for presenting blanks successively to the chases of type on the form cylinder, and while having advantages peculiar to a press of this type, may be employed to advantage with other types as well.

The frame of the machine is denoted by 1, the drive shaft by 2, the form cylinder by 3, and the impression cylinder by 4. The form cylinder is continuously rotated by the drive shaft through a pinion 5 on the drive shaft in mesh with a spur wheel 6 on the form cylinder shaft and the impression cylinder is continuously driven at variable rates of speed by the form cylinder through a special arrangement of inter-coating mated gears. The form cylinder is here shown as provided with two flat beds for receiving type chases and the impression

cylinder with two impression segments arranged to coat, one with each of the chases of type on the form cylinder.

The cam shaft is denoted by 7. It is driven directly from the drive shaft 2, 60 through interchange gear, not shown.

A set of delivery tapes 9 pass over a roll 10 carried loosely on the drive shaft 2, with its face in proximity to the face of the impression segment on the impression cylinder; thence the tapes 9 pass to and partially around a set of rimmed pulleys 11 fixed to rotate with the cam shaft 7 and which impart motion to the tapes, and thence to and around guide pulleys 12 mounted on a shaft 13, the shaft 13 being so located that the printed sheets resting on and traveling with the tapes from the roller 10 to the pulleys 12, will pass from the pulleys 12 directly into the receptacle 14, excepting when a second carrier is interposed. A second endless carrier consists of a set of tapes 15, passing around pulleys 16, fixed on a sleeve 17 loosely mounted on a shaft 18 journaled in suitable bearings carried by brackets 19, 20, 80 attached to the frame 1, and thence around pulleys 21 carried by a floating shaft 22 supported in arms 23, 24, fixed to and extending rearwardly from the shaft 18. The floating shaft 22 is located sufficiently near the pulleys 12 to cause the set of tapes 15 to receive a printed sheet as it leaves the set of tapes 9, whenever the said floating shaft and hence the rearward portion of the endless carrier, is rocked into its depressed position 90 below the plane of travel of the sheets on the tapes 9. The shaft 18 and hence the arms 23, 24, are rocked at predetermined intervals by a pitman 25, connected at one end to a crank 26 on the shaft 18, and at its opposite end, forked to embrace a projection 27 on the end of the impression cylinder shaft and provided with a laterally projecting pin 28 with antifriction roller 29 in position to be engaged by a cam 30 carried by a collar 31 fixed on the projection 27. The cam 30 will force the pitman 25 endwise once during each revolution of the impression cylinder and thereby rock the shaft 18 in a direction to lift the floating shaft 22 100 and hence rearward portions of the tapes 15, and so maintain it while a sheet from one of the impression segments is being deposited into or onto the receiver 14 and the shaft 22 and parts carried thereby will then 110

be allowed to drop so as to direct the next succeeding sheet onto the tapes 15 and hence deposit the sheet into the receptacle 32. The tapes 15 are actuated by a belt 33 driven by 5 a pulley 34 fixed on the cam shaft 7 and extending around a pulley 35 fixed on the sleeve 17.

In practice I prefer to use three tapes in the set 9, and four in the set 15, the individual tapes 15 alternating with the tapes 9 and affording a somewhat wider spread for the set of rocking tapes to guard against any unintentional slipping of a sheet off the set to one side.

15 The above simple arrangement of delivery tapes serves to place the successive printed sheets when both impression segments are in use, different piles affording the sheet last deposited an interval of time to dry, to wit: 20 an interval corresponding to the time required to deliver a successive sheet before it is disturbed by the falling of another sheet on it; and, when the two chases of type on the form cylinder present independent 25 subject matter, as for instance, labels for different garden seeds, the two jobs may be carried on at one and the same time, the labels printed on the bags to contain one kind of seeds being deposited in one pile, for instance in the receiver 14, and those to contain seeds of a different kind in another pile in the receiver 32.

When, as in the present illustration, the middle portion of the flat bed on the form 35 cylinder rotates in a path at a considerable less distance from the axis of the cylinder than the end portions of said bed, it is feasible to locate the upper roller for the tapes 9 only as near the flat bed as will permit 40 the end portions thereof to freely pass and the sheet to be printed must be held by the grippers until its gripped edge has passed between the tapes 9 and the impression segment at which moment the grippers

are positively released by their actuating 45 cam and the sheet left free to travel with the tapes.

By disconnecting pitman 25, sheets from both impression segments may be delivered into one receiver, in the present instance into 50 the receiver 32.

What I claim is:

1. In combination, a form cylinder provided with a plurality of forms, an impression cylinder provided with a plurality of impression segments arranged to coact with the said forms, a plurality of receptacles and a selective delivery mechanism in coactive relation with the said form and impression cylinders and including a set of tapes 60 mounted at their ends toward the cylinders on a floating shaft, for depositing successive printed sheets from the plurality of impression segments into different receptacles.

2. In combination, a form cylinder provided with a plurality of forms, an impression cylinder provided with a plurality of impression segments arranged to coact with the said forms, a plurality of receptacles and a selective delivery mechanism comprising a set of tapes permanently located in space, a second set of tapes mounted at one end on a floating shaft and adapted to swing into and out of the plane of the first named set to direct successive sheets from the plurality of printing segments into different receptacles and a pitman connected with the impression cylinder shaft for swinging the set of swinging tapes at the desired intervals.

In testimony, that I claim the foregoing 80 as my invention, I have signed my name in presence of two witnesses, this 21st day of January 1910.

HENRY B. COOLEY.
